(57) **CLAIM**

The ornamental design for a kettle grill bracket, as shown and described.

DESCRIPTION

FIG. 1 is a top left perspective view of a kettle grill bracket showing my new design;

FIG. 2 is a front view thereof;

FIG. 3 is a top view thereof;

FIG. 4 is a bottom view thereof;

FIG. 5 is a rear view thereof;

FIG. 6 is a left side view thereof; and,

FIG. 7 is a right side view thereof.

The broken lines in the figures show portions of the kettle grill bracket that form no part of the claimed design.
